UNITED STATES PATENT OFFICE.

VINE D. SIMAR AND JOHN DALE, OF ST. PAUL, MINNESOTA.

EXCAVATOR.

SPECIFICATION forming part of Letters Patent No. 278,368, dated May 29, 1883.

Application filed August 25, 1882. (No model.)

To all whom it may concern:

Be it known that we, VINE DORANCE SIMAR and JOHN DALE, both citizens of the United States, and both of St. Paul, in the county of Ramsey and State of Minnesota, have jointly invented certain new and useful Improvements in Excavators, of which the following is a specification.

This invention relates to excavators; and it consists in the construction and arrangement of parts, as hereinafter shown and specifically claimed.

In the drawings, Figure 1 is a side view. Fig. 2 is a plan view. Fig. 3 is an enlarged perspective view of one of the buckets and its chains. Fig. 4 is an enlarged sectional view of the lower shaft of the main excavator and two of the buckets, illustrating the manner of dumping the load.

20 A is the track, upon which a circular frame or turn-table, B, is adapted to be run back and forth by ordinary flanged wheels, C. This track may be made in any suitable manner, either sections of railroad-rails, as shown in the drawings, or wooden frames made for the purpose and laid over temporary ties, the track being merely for a temporary support for the machinery, and will be laid down in front of it as fast as it advances into the excavation.

30 When used in railroad-work the regular track may be laid as fast as the machine advances.

Upon top of the circular frame B is mounted by wheels D, and adapted to run around upon the circular frame, another frame, E, which carries the excavating machinery.

40 F is an endless belt of one or more chains running over drums G' G², one below the lower side of the frame E, on one side, and the other above the frame E, on the other side, the belt thus running at an angle of about thirty degrees. Across this belt, at regular intervals, buckets a are secured, and adapted, when the belt is revolved, to dig into the earth, as shown at H', and carry it up and dump it into a chute, I. Between the buckets the chains are covered with canvas to hold the earth.

Two endless chains, M, are arranged to run over chain-pulleys M', secured in a frame, N, the lower end of the frame adjustable higher

50 or lower in slots b in standard P, or by other

suitable means, and the upper end held at any angle by a guy-rope or chain, d', operated by a windlass or other power, d². Connected to these chains M at regular intervals, and adapted to run with them, are scoops or buckets R, having an open front end and top and closed rear end and bottom, as shown in Fig. 3, which represents the construction of these buckets. By this means, when the chains M are revolved in the direction of the arrows and the frame 60 N adjusted to lie in a line parallel with the bank, H², of earth to be excavated, the buckets R will cut into the earth and cut it down and convey it down to the traveling belt F, where the buckets a catch it and convey it up and 65 deliver it upon the chute I. The buckets R, in running down through the earth, will draw down ahead of them a much larger amount of earth than their interior will hold, which will be fed directly to the buckets a, while the earth 70 that remains in the buckets will be carried up around the lower pair of chain-pulleys, M', and dumped out of the back end of the buckets as they turn over in commencing the return movement, as shown at z in Figs. 1 and 4. 75

By lowering the frame N down as the earth is cut away by the buckets, a channel may be cut into the bank from the top to the bottom, or even below the bottom, as the upper end of the frame may be lowered down below the 80 level of the track. Then the machine is moved sidewise and another cut made if it is desired to widen the cut, or moved forward if it is desired to cut farther into the bank; or by swinging the apparatus around on the turn-table B 85 a semicircular cutting of a radius the length of the frame N may be excavated.

Midway between the buckets R colters or cutters h are arranged upon the chains M, and projecting down between the buckets, and 90 adapted to loosen the earth in front of the sides of the buckets to assist them in their work.

The chute I will usually be high enough, so that a wagon or car may be run beneath it and 95 be filled. A drop-door, i, will be arranged upon the bottom of the chute I, so that the falling earth may be shut off while the wagons or cars are being changed.

Another feature of this apparatus is that in 100

railroad-excavations, after the cut is made through a hill, the frame N may be turned and adjusted to the required slope of the sides of the cut, and the machine moved along and the 5 sides of the cut dressed down in a symmetrical form.

The dotted lines *m* represent the engine and boiler for operating the apparatus, which may be either mounted upon the same frame with 10 the apparatus, as shown, or set at a distance and connected therewith by a belt or other means of transmitting power.

In some kinds of soil the buckets R may be removed and a series of rakes or picks placed 15 upon the chains to rake or pick the soil down upon the belt F; or picks or rakes and buckets may be arranged alternately upon the chains.

Several sizes of the frames N may be furnished with each machine, and the chains M adapted to be shortened or lengthened to adapt 20 the machines to banks or cuts of varying depths or heights.

What we claim as new is—

- 25 1. In an excavating-machine, the combination of a series of buckets on an endless chain, a supporting-frame for said chain of buckets, laterally adjustable, so as to follow the slope of the bank being cut, and an endless chain of 30 cutting and delivery buckets below and in advance of the first series of buckets, so as to cut below and in advance of said buckets and receive the earth therefrom, substantially as and for the purpose set forth.
- 35 2. In an excavating-machine, the combination of a turn-table frame, a frame connected

thereto and made laterally adjustable, so as to follow the slope of the bank being cut, an endless chain of buckets connected to the adjustable frame, so as to cut downward, and a receiving and delivery platform to receive the dirt at the lower end of the adjustable frame as it is discharged from the buckets, whereby the cutting-buckets will cut downward and follow the slope of the bank, and can be turned 45 to cut on different sides of the machine, substantially as and for the purposes set forth.

3. In an excavating-machine, an endless belt carrying excavating-buckets adapted to be adjusted to fit and follow the slope of the earth 50 being acted upon, and revolved to cause said buckets to travel through the earth being excavated, from the outer toward the inner end of said chain of buckets, in combination with an endless belt, F, provided with combined 55 buckets and cutters *a*, substantially as herein-before shown.

4. The combination of the endless chains M, having buckets R, and running over suitable pulleys, and mounted in an adjustable frame, 60 N, endless belt F, having combined buckets and cutters *a*, chute I, base-frame E, turn-table B, and track A, substantially as herein-before shown.

In testimony whereof we have hereunto set 65 our hands in the presence of two subscribing witnesses.

VINE DORANCE SIMAR.
JOHN DALE.
